UNITED STATES PATENT OFFICE

HERBERT B. JOHNSON, OF LARCHMONT, NEW YORK

CENTRIFUGAL BASKET AND LINING THEREFOR

Application filed May 14, 1930. Serial No. 452,288.

The present invention relates to filtering apparatus of which centrifugal basket constructions are a type, and to filter media to be used therewith.

In the art of filtering or separating solids from liquids by means of fabric or metallic screen lined centrifuges, great difficulty has been experienced in that due to the tremendous centrifugal force developed in such devices, there is a leakage of solids around the top and bottom edges of the filter cloth, with consequential loss in filtering efficiency. This leakage may be due to failure to correctly fit the filter fabric closely and tightly in place in the perforated centrifugal basket, or unevenness or non-uniformity of height of the fabric. The usual practice is to manually place a filter cloth in position within the centrifugal basket and then retain the same there by means of internal metallic bands of substantial width overlying the cloth, in conjunction with bolts expanding the bands and clamping the fabric between the band and the inner wall of the centrifuge. Such expedients are far from satisfactory, due to the fact that it is difficult to prevent leakage from the cloth so held and the basket itself. The basket and its accompanying bolts also throw the centrifuge off balance, which is extremely dangerous when running at high speed. Fitting and replacement of such arrangements covers a long period of time, requiring expert labor, and due to corrosion of such metallic parts, replacements of cloths are extremely difficult.

The principal objects of the invention are, therefore, to provide a filtering apparatus of a construction in which a cloth or fabric may be readily placed or replaced, and in a manner which will produce efficient filtration with minimum leakage of solids, and which in a centrifuge will maintain the balance thereof during operation. These and other objects are obtained with an apparatus of special design, and by means of a filter fabric constructed as hereinafter described.

One aspect of the invention contemplates the provision of a centrifugal basket with an upper and lower circumferential groove lo-

cated on the inner face of the basket and axially beyond the perforated area thereof. These grooves preferably extend in a direction parallel to the basket axis, although this is not essential. A filter cloth or fabric may then be fitted to the basket interior so as to cover the perforated area, the longitudinal edges thereof lying in the respective grooves of the basket. Wicking or other suitable strip packing may then be placed in the grooves over the cloth to seal against leakage of solids. Upon the development of centrifugal force in the basket, the packing will be forced tighter and tighter against the filter cloth edges and this effectively prevents leakage.

It is desirable that a filter cloth or fabric be used having flexible spring elements therein or thereon to insure rigidity and correct fitting of the fabric. These elements may consist of parallel spaced apart strips of bamboo, wire, or the like and arranged in the cloth so as to occupy a position parallel to the basket axis. On the other hand, such strips or wires may consist of a circumferential wire or bamboo strip in proximity to the upper and lower edge of the cloth and adapted to lie within the aforesaid grooves. As a further modification, the fabric may have applied to it rows of a liquid or plastic material which upon subsequent treatment will acquire a desired degree of stiffness or hardness. These rows of hardened material may be on either or both sides of the fabric and in the latter case, be arranged at an angle to each other. These stiffening strips may be either flush with the fabric surface or project therefrom and where on the basket side of the fabric will serve to space the filter medium from the basket wall. When on the opposite or exposed side of the fabric, such beads will serve to protect the cloth from injury in unloading the cake by reason of the fact that the unloading or scraping blade will contact with the bead rather than the cloth. The invention contemplates either or both arrangements.

The invention further consists in the novel arrangement, combination and construction

of parts, more fully hereinafter described and shown in the accompanying drawings.

In the drawings:—

Fig. 1 is a fragmentary sectional view of a centrifugal basket embodying the invention.

Fig. 2 is a fragmentary sectional view of a modified basket.

Fig. 3 is a similar view of still another form.

Fig. 4 is a view of a filter cloth embodying the invention.

Fig. 5 is an edge view of the cloth of Fig. 4.

Fig. 6 is a view of a modified cloth.

Fig. 7 is a sectional view of a basket with a filter cloth in place.

Fig. 8 is a view of another form of cloth.

Fig. 9 is a view of still another form of cloth.

Referring now to those embodiments illustrated, there is shown diagrammatically at 1 a perforated wall of a centrifugal basket of any desired construction, and mounted for rotation in the usual and well-known manner. It is to be understood that while a centrifugal type of filter apparatus is shown, yet the invention is applicable to any type of separation equipment utilizing a filter cloth or fabric. Within this basket a filter cloth 2 of fabric is placed so as to cover the perforated area of the wall and retain the solids thereon, the liquid menstruum passing through the wall, all as is well-known in this art. A mesh screen 2^a is usually placed between the filter medium and the basket wall.

25 to space the two apart and permit escape of the liquid through the perforated basket wall.

In practicing the invention, it is preferable to provide an upper groove 3 and a lower groove 4 beyond the perforated area, extending circumferentially of the basket and substantially parallel to the axis thereof. In fitting the cloth to the basket interior, the upper and lower longitudinal edges thereof are placed in the grooves 3 and 4

45 respectively. Wicking or other suitable packing 5, preferably of a strip nature, may then be used to fill the grooves and completely cover the edges of the cloth 2. This packing may be of a more dense nature in order to insure the prevention of leakage therethru and around the edges of the filter cloth. Upon rotation of the basket, this packing will be forced into the groove under centrifugal action or the flowing fluid and tends 55 to more completely seal the edges of the cloth against leakage of solids and thus insure high filtering efficiency. This packing may be accentuated by arranging the grooves at an angle, somewhat as shown at 6 in Fig. 2.

60 Centrifugal baskets of usual construction, to wit, without the grooves of this invention, may be readily supplied with such feature either by actually cutting the grooves into the wall thereof or by providing a substantially L-shaped circumferential band 7 at

the top and bottom of the side wall thereof, as shown in Fig. 3. Such elements 7 may be provided with a projecting portion 8 which forms beyond this and the basket 1 a groove within which the edge of the filter cloth may be fitted. The strip 7 may be secured in place by any desired means, such as cement, or by screws or the like 9. Obviously this band may be integral or in sections to facilitate placing and replacing as desired.

70 While the broad invention contemplates the use of ordinary filter cloths or fabrics, yet the efficiency of the device as a whole may be greatly increased, particularly in the time saved by placing and replacing the filter medium, by use of a fabric bearing stiffening or spring elements therein or thereon. Such a filter medium is shown in one form to consist of a woven fabric of any desired weave, in connection with spring elements of wire, bamboo, or other flexible material. Such strips may be, and preferably are, woven into the cloth. These spring strips 75 are of a length equal to the distance between the top and bottom grooves. The ends of the strips may be strung into the grooves, thus carrying the fabric edges thereinto and holding the fabric in place until the wicking can be placed. Likewise, this construction holds the fabric firmly to the basket walls during the scraping and unloading operations. To remove the cloth, the spring elements are simply sprung out of the groove 80 after removing the wicking.

85 In addition to the ease of fitting and replacement of the cloth of the above design, it has the added advantage of being much stronger than one without such strips. It will be apparent that as the retained filter cake builds up, a greater load is placed on the basket by centrifugal force. The presence of such strips aids materially in keeping the cloth or fabric tightly in place and carrying the thus accumulating load.

90 In another form, the spring elements may be arranged in the longitudinal edges of the cloth as in Fig. 6. Here the elements comprise wires 12 and are enclosed within a hem 13 of the cloth, and adapted to lie within the grooves, as heretofore. Such a construction permits the cloth edges to be rapidly and quickly sprung into the grooves and overlaid with packing.

95 When it is not desired to enclose the wires 12 in a hem in the cloth, they may be separate therefrom and in one case lie in a back fold 14 as shown in Fig. 7. This arrangement of parts holds the edges of the cloth firmly against sagging and the wicking seals the same as above described. To remove the fabric thus held, it is only necessary to pull out the strip wicking, slip out the wire and remove the cloth.

100 The invention contemplates either the overlapping of the ends of the fabric so as to

completely seal the perforated area of the basket wall, or the weaving of the cloth into an endless annulus. Likewise, the wire or strips of bamboo 12 may be a simple length thereof or have their edges secured together so as to closely fit within the grooves.

In still another form the stiffening may be applied to the fabric as a liquid or semi-liquid and brought to the desired degree of hardness or stiffness by subsequent treatment. Such a material may be chosen from the well-known class of substances like bakelite, latex, synthetic resins, various flexible porcelains, cements, superimposed layers of rubber or cement and metallic strips or the like. Such materials may be made to actually soak into the cloth and upon subsequent treatment harden into a strip, the outer surface of which is flush with the surface of the fabric as at 15 in Fig. 8, or form a dried up bead as at 16 in Fig. 9. This latter figure also shows a series of beads 17 in the opposite side of the fabric, at an angle to the beads 16. This not only tends to stiffen the filter media, but spaces the cloth from the basket wall and thus enables one to dispense with the mesh material 2. Where the beads of stiffened or hardened material are arranged circumferentially on the exposed side of the cloth, the unloading knife or scraper in removing the cake, may contact therewith and thus prevent damage to the cloth in this operation.

While the invention has been shown and described with particular reference to certain types of filtering apparatus, such as centrifuges, and filtering cloths, yet obviously it is not to be limited thereto, but the invention is to be construed broadly and restricted only by the scope of the claims.

I claim:

1. In combination, a centrifugal basket having a peripheral groove, and a lining for the basket walls extending into said groove, an integral portion of the basket wall overlying the peripheral edge of the lining.
2. In combination, a centrifugal basket having a peripheral groove, a lining for the basket walls extending into said groove, an integral portion of the basket wall overlying the peripheral edge of the lining, and packing means overlying an edge of the lining and also within the groove.
3. In combination, a centrifugal basket having an interior peripheral groove at the top and an interior peripheral groove at the bottom thereof and each defined by walls integral with the basket and extending substantially vertically and concentric with the basket axis, a lining for the basket, the peripheral edges of the lining extending into said grooves.
4. In combination, a centrifugal basket having grooves in the basket wall, a lining therefor, and spring means to maintain the

lining tight against the basket walls, the ends only of the spring means extending into the grooves in the basket wall.

5. In combination, a centrifugal basket having grooves in the basket wall, a lining therefor, and spring means to maintain the lining tight against the basket walls, said spring means extending vertically into the grooves at the top and bottom of the basket walls.

6. In combination, a centrifugal basket, a lining therefor, and spring means to maintain the lining tight against the basket walls, said spring means being woven into the lining.

7. In combination, a centrifugal basket having a perforated wall, a strip secured within the basket and beyond the perforated portion, a groove in said strip, and a lining covering the perforated portion of the basket and extending into said groove.

8. A filtering cloth or media consisting of a tightly woven cloth fabric and spaced apart spring means woven thereinto and capable of maintaining the cloth flat against a tendency to sag.

In testimony whereof, I have hereunto subscribed my name this 13th day of May 1930.
